UNITED STATES PATENT OFFICE.

EMIL E. EHRLICH, OF CITRUS PARK, FLORIDA.

SLICING AND SAWING DEVICE.

1,290,528.

Specification of Letters Patent.

Patented Jan. 7, 1919.

Application filed November 26, 1917. Serial No. 203,992.

To all whom it may concern:

Be it known that I, EMIL E. EHRLICH, a citizen of the United States, residing at Citrus Park, in the county of Hillsborough and State of Florida, have invented a certain new and useful Improvement in Slicing and Sawing Devices, of which the following is a full, clear, concise, and exact description, reference being had to the accompanying drawings, forming a part of this specification.

The invention relates to slicing and sawing devices, and has for its object the production of a unitary arrangement whereby either a knife or saw edge may be presented to the material, the character of the material to be cut determining which appliance is to be used, to sever the slice from the piece from which it is cut.

The invention has as a further object the provision of a simple and effective construction whereby either of the above named appliances may be brought into position to result in the accomplishment of the desired end, and which is capable of operation in conjunction with a suitable driving mechanism, as for instance such as shown and described in my application Serial No. 133,637, filed November 27, 1916, which permits the saw or knife to be reciprocated and properly positioned to cause the cutting or sewing to be accomplished.

The invention further contemplates the provision of a means to control the reciprocation of the saw or knife, this means being applied near the handle of the device where it will be readily accessible. All of these features together with others will be more readily apparent from a detailed description of one form of carrying out my invention which is shown in the accompanying drawings, in which

Figure 1 is a side elevation of the invention showing the knife or saw frame in one of its extreme positions of reciprocation;

Fig. 2 is a section taken on line 2—2 of Fig. 1, showing a means for causing the knife or saw edge of the blade to be presented to the material; and

Fig. 3 is a fragmental view similar to that shown in Fig. 1, showing the parts in alternate position.

The embodiment of the invention shown in the drawings contemplates the use of a saw frame 10 having the blade 11, the opposite edges of the blade being provided with

the saw teeth 12 and the knife edge 13. This saw frame 10 is mounted upon the frame 14 having the handle 15. The frames 10 and 14 are connected together by the pins 16 and 17 which are passed through the slots 18 and 19 of the frame 10 and into the frame 14 holding these parts together. Upon the upper part of the frame 10 is mounted the tread 20 with which co-operates the segmental tread or driver 21 which is actuated back and forth by the crank 22 and the link 23 connecting the segment and the crank. This crank 22 is driven by the flexible shaft 24. By this arrangement it can readily be seen that as the crank 22 is rotated the frame 10 having the blade 11 will be reciprocated and will either saw or slice the material depending upon which the edges of the blade 11 are presented thereto. The frame 14 and its associated parts are suspended from the hanger 25 which may be raised and lowered as described in my application Serial No. 133,637. This frame 14 and its associated parts are also pivotally connected to the hanger 25 by the link 26 which is pivoted thereto at 27. The link has its opposite end secured to the frame 14, and by virtue of its pivotal connection with the hanger, the frame is permitted to assume various angular positions. By the arrangement just described the saw or knife frame may be reciprocated, raised and lowered, and shifted to various angular positions from the horizontal and vertical. This provides for the various positions which a device of this character may be subjected to.

The means whereby the blade 11 is rotated to present either edge thereof to the material to be cut includes a lever 29 which is pivoted at 30. The forward end of the lever extends beyond the rear end of the frame 10 when this frame assumes its extreme position in this direction. The opposite end of the lever extends downwardly and is provided with the portion 31 which forms a handle. This portion extends beyond the hand hole 32 and is accessible to be grasped by the operator to manipulate the shifting mechanism which operates the blade 11. The saw frame 10 nearest the handle 15 has mounted upon it the bar 33 which is secured to the frame by the screw 34 which operates in the slot 35. This bar 33 is further provided with the pin 36 having one end of a spring 37 secured to it. The other end of this spring is secured to the screw

34 which operates in the slot 35. This spring holds the bar 33 and the lever 29 in an upward position, the slot 35 limiting this upward movement. The uppermost end of the bar 33 is hooked over one end of the lever 29, as shown at 40, and is provided with the roller 41 which bears against the under side of said lever. Thus this lever is restored to its upward position by the spring 37 when released from the grasp of the operator. The opposite end of the bar 33 carries the link 42 which is connected to the arm 43 of the segmental gear 44 which is pivoted to the frame 10 by the screw 45. The teeth of the segment 44 engage the segmental pinion 46, the shaft of which extends through the journal 47 in the frame 10 and has secured to it one end of the blade 11. The segment 46 and the journal 47 having their adjacent ends provided with the serrations 48 which assist in holding this end of the blade 11 in its vertical or adjusted position, yet permits the blade 11 to be easily adjusted by the adjusting mechanism. The opposite end of the blade 11 is provided with a shaft 49 which extends through the journal 50. This shaft and journal are also provided with a means 51 for holding it in its adjusted position. The end of this shaft 49 extends beyond the journal 50 and is screw threaded to take the winged nut 52 which acts against the coiled spring 53 which reacts between this nut and the journal 50 and holds the parts in their proper relation but permits them to be adjusted when occasion demands.

The handle 15 is provided with contact making elements 53, 54 and 55, which are operable by the end or handle 31 of the lever 29 and the push button mechanism 56. These contact making elements control the motor which drives the flexible shaft 24 and the elements connected thereto. The push button mechanism 56 being operable to close the contacts and operate the device when the blade 11 is in the position shown in Fig. 1. The end or handle 31 of the lever 29 is provided with an insulating pin 57 which when the lever 29 is operated to present the saw edge to the material to be cut, closes the circuit through the springs 53 and 54, throwing the motor into operation to drive the saw frame 10.

While I have herein shown and described a contact element which is operated by the handle 31 and the push button 56, it is evident that only the push button 56 need be depended upon to cause the operation of the motor, thus eliminating the contact spring 53 and the insulating pin 57.

By referring to Figs. 1 and 3, it will be seen that when the lever arm 29 is in either of the positions shown, the reciprocation of the frame 10 will not affect the mechanism which causes the blade 11 to be shifted. The

opposite edges of this lever are designed so that either of the same will be in substantial alignment with the travel of the frame 10, when said lever is in either of its two positions, thereby eliminating the possibility of actuating the shifting mechanism for the blade during the reciprocation of the frame. It will also be understood that any suitable mechanism may be resorted to instead of the gears 44 and 46 for causing the opposite edges of the blade to be presented to the material to be cut, and while I have herein shown and described one form which the invention may take, what I claim and desire to cover by Letters Patent is:

1. A device of the class described comprising in combination, a frame, a blade arranged in the frame, the opposite edges of the blade being provided with cutting edges, one edge of the blade being normally presented to the material to be cut, means for presenting the opposite edge thereto and restoring the first mentioned edge to its first named position.

2. A device of the class described comprising in combination a frame, a cutting blade arranged in the frame, said blade having distinctive cutting edges, one of which is normally presented to the material to be cut, means for presenting the other edge to the material to be cut and for automatically restoring the first named edge to its normal position.

3. A device of the class described comprising in combination a frame, a cutting blade arranged in the frame, said blade having distinctive cutting edges, one of which is normally presented to the material to be cut, means for presenting the other edge to the material to be cut and automatic means for restoring the first named edge to its normal position.

4. A device of the class described comprising in combination a reciprocable frame, a cutting blade arranged in the frame, said blade having distinctive cutting edges one of which is normally presented to the material to be cut, means for presenting the other edge to the material to be cut, and means for automatically restoring the first mentioned edge to its normal position.

5. A device of the class described comprising in combination, a reciprocable frame, a cutting blade arranged in the frame, said frame being mounted between its ends to permit its adjustment to various angular positions, and means for actuating the blade to present either edge thereof to the material to be cut.

6. A device of the class described comprising in combination, a frame, a cutting blade arranged in the frame, a support for the frame, said frame being reciprocable with relation to the support, and co-operating means arranged upon the frame and the sup-

- port for actuating the blade to present either edge thereof to the material to be cut, said means being pivoted transverse to the axis of said blade.
- 5 7. A device of the class described comprising in combination, a frame, a blade having two cutting edges arranged in the frame, and means for presenting either edge of the blade to the material to be cut, said frame 10 being movable, and means operable by the first mentioned means for controlling the operation of the movable frame.
8. A device of the character described comprising a frame, a blade having two distinctive cutting edges carried by the frame, a support including a handle on which the frame is reciprocably carried, means whereby the blade normally presents a cutting edge to the material to be cut, means to at will 15 control the presentation of the other cutting edge to the material to be cut and means carried by the support to control the reciprocation of the frame, the means for presenting said edges to the material to be cut 20 being arranged upon the frame and the support.
9. A device of the class described comprising in combination, a frame, a cutting blade arranged in the frame, the opposite edges 25 of which are provided with cutting edges, a support for the frame, said frame being movable with relation to the support, and means for presenting either edge of the blade to the material to be cut, said means being mounted upon the movable frame and the support.
10. A device of the character described comprising a frame, a blade having two distinctive cutting edges carried by the frame, 30 a support including a handle upon which the frame is reciprocably carried, means whereby the blade normally presents a cutting edge to the material to be cut, means to at will control the presentation of the 35 other cutting edge to the material to be cut, said means including a lever carried by the support.
11. A device of the class described comprising in combination, a frame, a movable 40 frame mounted upon the first mentioned frame the opposite edges of which are provided with cutting edges, a cutting blade arranged in the movable frame, means for turning the blade to present either edge 45 thereof to the material to be cut, said means being mounted on said movable frame, and means for actuating the means for turning the blade, said means comprising a lever mounted upon the first mentioned frame.
- 50 12. A device of the class described comprising in combination, a frame, a blade arranged in the frame, one edge of the blade being normally presented to the material to be cut, means for presenting the opposite 55 edge thereto and restoring the first mentioned edge to its first named position.
13. A device of the character described comprising a frame, a blade having two distinctive cutting edges carried by the frame, a support including a handle on which the frame is reciprocably carried, means whereby the blade normally presents a cutting edge to the material to be cut, means to at will control the presentation of the other cutting edge to the material to be cut and means carried by the support to control the reciprocation of the frame when either of the cutting edges are presented to the material to be cut.
14. A device of the character described comprising a frame, a blade having two distinctive cutting edges carried by the frame, a support including a handle on which the frame is reciprocably carried, means whereby the blade normally presents one of said cutting edges to the material to be cut, means to at will control the presentation of the other cutting edge to the material to be cut and means carried by said support to control the reciprocation of the frame when the first mentioned edge is in operable position.
15. A device of the character described comprising a frame, a blade having two distinctive cutting edges, means whereby said blade normally presents a predetermined cutting edge to the material to be cut and means to at will temporarily nullify the action of said first aforesaid means and to control the presentation of the other cutting edge to the material to be cut.
16. A device of the character described comprising a frame, a blade having two distinctive cutting edges carried by the frame, a support including a handle on which said frame is reciprocably carried, means whereby said blade normally presents a predetermined cutting edge to the material to be cut, means to at will control the presentation of the other cutting edge to the material to be cut and means carried by said support to control the reciprocation of said frame.
17. A device of the character described comprising a frame a blade having two distinctive cutting edges carried by the frame, a support including a handle on which said frame is reciprocably carried, means whereby said blade normally presents a predetermined cutting edge to the material to be cut, means to at will control the presentation of the other cutting edge to the material to be cut said means being arranged upon the support and the frame and being movable with relation to the frame and the support.
18. A device of the class described comprising a frame a blade having two distinctive cutting edges carried by the frame, a support including a handle on which said

- frame is reciprocably carried, means whereby said blade normally presents a predetermined cutting edge to the material to be cut, means to at will control the presentation of 5 the other cutting edge to the material to be cut said means being arranged upon the support and the frame and being movable with relation to the frame and the support, and means carried by the support for controlling the reciprocation of the frame.
19. A device of the class described comprising a frame, a blade having two dis-

tinctive cutting edges carried by the frame, a support for the frame, means whereby the blade normally presents a cutting edge to the material to be cut, means to at will temporarily control the presentation of the other cutting edge to the material to be cut said means being carried by the support.

In witness whereof, I hereunto subscribe my name this 15th day of November A. D., 1917.

EMIL E. EHRLICH.
